UNITED STATES PATENT OFFICE

2,488,877

LOCOMOTIVE DRIVING WHEEL CENTER

Oscar Carl Peterson, West Allis, Wis.

Application October 9, 1946, Serial No. 702,137

6 Claims. (Cl. 295—6)

1

This invention relates to applying the recommendations of the "A. A. R. Manual of Counterbalance for Reciprocating Steam Locomotives," July 1, 1945, which provides a main counterbalance for the crank pin and other parts associated with each driving wheel and a cross counterbalance, or auxiliary counterbalance, for the things associated with the opposite driving wheel on the same axle.

A difficult problem arises in providing a driving wheel for use on several classes of locomotives using the same size of wheels but having different counterbalance conditions. And the specific object of this invention is to provide for varying the amount of counterbalance to suit different requirements without disturbing the center of gravity of that material or varying its position laterally.

Generally speaking, this is accomplished by forming a pocket in the wheel large enough for the greatest amount of counterbalance material to be used and reducing the capacity of the pocket in other instances by placing a tube of suitable size across the pocket centrally and inserting the counterbalance material, such as molten lead, in the pocket around the tube.

Fig. 1 is a side elevation of a driving wheel center embodying this invention;

Fig. 2 is a cross section taken on the line 2—2 of Fig. 1;

Fig. 3 is a fragment of a side elevation corresponding to Fig. 1 showing a modification; and

Fig. 4 is a transverse section taken on the line 4—4 of Fig. 3.

But these specific drawings and the corresponding description are chosen for the purpose of disclosure only and merely illustrate the invention. They are not intended to impose any unnecessary limitations on the claims.

Fig. 1 shows a driving wheel center, generally indicated by 10, having a main hub 11 and a crank pin hub 12. On the side of the wheel center 10, opposite to the crank pin hub 12, is a main counterbalance indicated generally by 13. As all of these things are somewhat a matter of selection as to general construction and detail, this general description is deemed sufficient.

A cross counterbalance or auxiliary counterbalance arrangement is shown generally at 14 in Fig. 1 and in section in Fig. 2. The basis of this arrangement is a pocket defined by a circumscribing wall 15, a back wall 16 here shown as integral with the circumscribing wall and the wheel center, and a front wall 17 here shown as a separate cover plate made fast by three screws

2

18 and circumferential welding to the wheel center and the wall 15 at 19.

When the pocket is just large enough for the maximum amount of auxiliary counterbalance or cross counterbalance material, it is only necessary to remove the cover plate 17, insert the material (for example, molten lead), replace the cover plate 17, insert the screws 18, and do the welding 19.

When the counterbalance conditions require a less amount of counterbalance material, the cover plate 17 is bored out centrally at 20 to receive a tube 21, which is inserted through that bored opening until its inner end rests against the back wall 16, when it is welded to that wall, as indicated at 22. Then the cover plate 17 being removed, the counterbalance material is poured into the space and fills the annular portion of the pocket as indicated at 23. Thereafter, the cover plate 17 is put on, fastened by the screws 18, and welded at 19. By varying the diameter of the tube 21, the amount of counterbalance material 23 may be varied to suit the conditions.

Another counterbalance arrangement is shown generally at 26 in Fig. 3, and in cross section in Fig. 4. In this instance, the pocket is defined by a circumscribing wall 115, a fixed rear wall 116, and a fixed front wall 117. As an incident to molding such a pocket in the wheel, there will be concentric core holes in each of the walls 116 and 117, one of which, 27, is shown at the left in Fig. 4, where it is filled with a disk or plug 28 secured in place by being welded at 29 to the margin of the core hole. The other core hole has

disappeared due to a boring operation by which a hole 30 is provided in the rear wall 116 to admit a tube 31, the outer end of which is brought against the wall 117 and welded thereto, as indicated at 32. The outer end is welded to the wall 116, as indicated at 33. The counterbalance 34 is then inserted into the annular pocket through a pouring hole 35 in the wall 117, after which that hole is closed by a threaded plug, or a welded plug, or both.

These two illustrations will serve to indicate to others how to vary the quantity of counterbalance material without shifting it laterally or throwing the center of gravity out of position, and they will vary the form of the pocket and the other details to suit personal preference and individual conditions.

I claim:

1. A locomotive driving wheel comprising, a wheel center having a concentric main hub and an eccentric crank pin hub, a main counterbal-

ance eccentrically mounted on said wheel center and having its center of gravity diametrically opposite the center of gravity of said crank pin hub, and an auxiliary cross counterbalance formed eccentrically in said wheel center having its center of gravity at a location spaced approximately ninety degrees from the respective centers of gravity of said main counterbalance and said crank pin hub and comprising a generally cylindrical pocket open at one end, a cylindrical tube secured at one end to the closed end of said pocket within and concentric with the latter to form an annular chamber, a cover plate secured to said tube and to said wheel center around said pocket to close said chamber, and counterbalance material molded within said chamber.

2. In a locomotive driving wheel center having a concentric main hub and an eccentric crank pin hub, an auxiliary cross counterbalance formed eccentrically in said wheel center having its center of gravity at a location spaced approximately ninety degrees from the center of gravity of said crank pin hub and comprising a generally cylindrical pocket open at one end, a cylindrical tube secured at one end to the closed end of said pocket within and concentric with the latter to form an annular chamber, a cover plate secured to said tube and to said wheel center around said pocket to close said chamber, and counterbalance material molded within said chamber.

3. The method of cross counterbalancing a locomotive driving wheel which includes forming a generally cylindrical pocket in the wheel, fixing centrally in the pocket a tube substantially smaller in diameter than said pocket to form with the walls of said pocket an annular space having a volume substantially equivalent to that filled by the weight of counterbalance material required to cross counterbalance said locomotive wheel, filling said pocket about said tube with said counterbalance material, and closing and reinforcing said pocket and resulting contents with a closure plate securely attached to said wheel.

4. The method of cross counterbalancing a locomotive driving wheel which includes forming a generally cylindrical pocket in the wheel, fixing centrally in the pocket a tube substantially smaller in diameter than said pocket to form with the walls of said pocket an annular space having a volume substantially equivalent to that filled by the weight of counterbalance material required to cross counterbalance said locomotive wheel, pouring molten counterbalance material into and substantially filling the annular space surrounding the tube, cooling and solidifying said

molten counterbalance material, and closing and reinforcing said pocket and resulting contents with a closure plate securely attached to said wheel.

5. The method of counterbalancing and cross counterbalancing a locomotive driving wheel having a crank pin hub thereon which includes the steps of providing a main counterbalance weight on said wheel having its center of gravity spaced approximately one hundred eighty degrees from the center of gravity of said crank pin hub, forming a generally cylindrical pocket in said wheel at a location spaced approximately ninety degrees from the centers of gravity of said crank pin hub and said main counterbalance weight, positioning in the central portion of said pocket a tube chosen from a plurality of tubes of different diameters to form with the walls of said pocket an annular space having a volume substantially equivalent to that filled by the weight of counterbalance material required to cross counterbalance said locomotive wheel, securely fixing said tube centrally to the back wall of said pocket, substantially filling the annular space thus provided within said pocket with counterbalance material, and closing and reinforcing said pocket and resulting contents with a closure plate securely attached to said wheel.

6. The method of crossbalancing a locomotive driving wheel which includes the steps of forming a generally cylindrical pocket eccentrically in said wheel, selectively positioning in the central portion of said pocket a tube chosen from a plurality of tubes of different diameters to form an annular space having a volume substantially equivalent to that filled by the weight of counterbalance material required to cross counterbalance said locomotive wheel, securely fixing said tube centrally to the back wall of said pocket, substantially filling the annular space thus provided within said pocket with counterbalance material, and closing and reinforcing said pocket and resulting contents with a closure plate securely attached to said wheel.

45 OSCAR CARL PETERSON.
